BEAM DEFLECTOR FOR CATHODE-RAY
TUBESMilton Emmer and James Edward Henschel,
Brooklyn, N. Y.

Application March 23, 1951, Serial No. 217,142

13 Claims. (Cl. 313—75)

1

The present invention relates to beam deflectors, especially those of the type associated with ion traps for cathode ray tubes.

The term "cathode ray tube" as used herein is intended to be generic, including all tubes which involve the use of a beam of electrons produced by an electron gun or similar device. The term is intended to include, for example, a television picture tube.

Cathode ray tubes commonly include electron guns which project a beam of electrons or cathode rays toward a target or a fluorescent screen. Such beams inherently include not only electrons but ions which may be produced in various ways, for example, by collision of the electrons with gas molecules. If such ions reach the target or screen, they may combine chemically with the material of the screen, causing it to lose its fluorescent characteristics. Such a phenomenon is referred to in the case of television picture tubes as an "ion burn." It is common to prevent such ion burns by constructing the tube so as to trap the ions and to prevent their reaching the target or screen. The trapping of the ions may be accomplished by constructing the electron gun so that it discharges the beam at an angle to the axis of the tube. The beam then passes a magnetic beam deflector which deflects the beam through a small angle so as to direct it toward a trap plate having an aperture in its center. Since the ions are heavier than the electrons, they are not deflected through the same angle by the magnetic beam deflector, but are instead deflected through a somewhat smaller angle. If the beam deflector is properly positioned with respect to the path of electron beam, then the beam of electrons will proceed through the aperture in the trap plate, while the ions impinge on the plate and are there collected.

The beam deflector may be located outside the glass wall of the tube, since its magnetic field will be effective through the glass. It is highly desirable that the beam deflector be mounted outside of the tube so that it may be adjusted to insure that the electron beam passes through the aperture in the trap plate. Such beam deflectors commonly comprise one or more permanent magnets and suitable supporting structure by which the magnets may be adjustably positioned on the neck of the tube. It is with such beam deflectors that the present invention is concerned.

An object of the invention is to provide a magnetic beam deflector which is easy and economical to manufacture. Another object is to provide a beam deflector which is compact and structurally simple.

A further object is to provide a beam deflector which will produce a concentrated magnetic field extending substantially diametrically across the neck of the tube.

2

Another object is to provide a beam deflector which may be adjustably positioned on the surface of a glass tube without scratching or damaging the glass. Another object is to provide a beam deflector which may be readily installed or removed from a tube, even though the tube may have a base of greater diameter than the glass neck which carries the beam deflector.

The foregoing and other objects of the invention are attained by constructing the beam deflector in the form of an annulus having two or more segments. These segments are formed of non-magnetic material substantially softer than glass, preferably moldable plastic material. The segments are provided with interfitting ends and are held in frictional engagement with the neck of the tube by means of an encircling tension band which may take the form of a rubber ring. The segments have their edges bevelled so as to slide readily over the tube. Each segment has a recess on its inner surface for receiving a magnet. The recess is deeper than the magnet, so that the magnet does not touch the tube.

The magnets may be provided with pole pieces so as to form two semi-circular magnetic members with their adjacent ends slightly spaced apart. When such magnets are arranged so that the adjacent ends are of like polarity, then they provide a concentrated magnetic field extending substantially diametrically across the neck of the tube.

In the accompanying drawings:

Fig. 1 is an elevational view of the inside surface of one segment of one form of beam deflector constructed in accordance with the present invention.

Fig. 2 is a side view of the segment shown in Fig. 1.

Fig. 3 is a plan view of a rubber ring which forms part of a complete beam deflector.

Fig. 4 is an assembly view showing a complete beam deflector mounted on the neck of a cathode ray tube.

Fig. 5 is a somewhat diagrammatic elevational view of a complete television picture tube, illustrating the relationship of the beam deflector, the tube base and the focusing coils.

Fig. 6 is an elevational view similar to Fig. 1, showing a modified form of beam deflector embodying our invention.

Fig. 7 is an assembly view showing a complete beam deflector of the type shown in Fig. 6, partly broken away.

Fig. 8 is an assembly view showing another modified form of a beam deflector embodying our invention.

Figs. 1 to 5

The complete beam deflector, best seen in Fig. 4, includes a pair of substantially semi-annular segments 1, which are held in frictional engage-

ment with the surface of the tube by means of an encircling tension band 2. This band may be a rubber ring, as illustrated, or it may be a coil spring or other equivalent structure.

The segments 1 are constructed of non-magnetic material which will not scratch or otherwise damage the surface of the glass. A moldable plastic material is preferred. The edges of the glass engaging surfaces of the segments 1 are bevelled, as shown at 3, as an aid in preventing damage to the glass and in sliding the beam deflector over the base of the tube.

Each segment is provided with a central axially extending recess 4 in its inner surface, for receiving a permanent magnet 5. The recess 4 is deeper than the thickness of the magnet 5, so that the magnet does not touch the surface of the glass tube. The magnet 5 may be cemented in place in the recess 4. The inner surface of the segments 1 may be hollowed out, as shown at 6, to save material.

The segments 1 are provided with interfitting end surfaces comprising substantially radial plane surfaces 8, one of which is provided with a projecting pin 9, formed integrally with the segment 1. The other plane surface 8 is provided with a recess 10 for receiving the pin 9 of the other segment.

It may be seen that if all the segments 1 and the magnets 5 are assembled with the polarities of the magnets in the same direction with respect to the position of the pins 9 and sockets 10, that the assembly of any two segments will result in a structure wherein the magnet poles which are diametrically opposite each other are of opposite polarity. Such an arrangement of the poles is necessary, since if the polarities of the diametrically opposite poles of equal strength were the same, the fields would buck each other and the net field existing near the axis of the tube would be very weak and substantially ineffective to deflect the electron beam.

Referring to Fig. 5, there is shown a television picture tube 11 on which is mounted a beam deflector generally indicated at 12 and constructed in accordance with the present invention. The tube has a base 11a whose diameter is substantially greater than that of the neck 11b on which the beam deflector is mounted. An ion trap plate 11c is mounted within the neck. The neck extends through a set of focusing coils 13 which cooperate with the beam to sweep it across screen 11d and to modify it as desired to produce the picture.

When the tube 11 is being mounted and dismounted on the chassis of the set, the neck 11a must be passed through the focusing coils 13. In order that the focusing coils may work as efficiently as possible, it is customary to make their internal diameter as small as possible while still permitting passage of the base 11a. Since the outside diameter of the beam deflector is larger than the inside diameter of the focusing coils, the beam deflector must be removed over the base before the tube can be dismounted. Similarly, the beam deflector must be installed over the base after the neck of the tube is inserted through the focusing coils 13.

When using a beam deflector constructed in accordance with the present invention, it is simple to separate the two segments far enough to expand the annulus so that it passes readily over the base 11a. Furthermore, the beam deflector is readily adjustable on the internal surface of the tube and is firmly held in frictional engagement

with that surface without damage to the surface.

The pins 9 are made long enough so that the two segments may be separated far enough to pass over the base without having the pins lose their engagement with their opposing sockets 10.

The segments are made with their end surfaces 8 separated by a distance slightly less than the periphery of a semi-circle, so that when the two segments are assembled on a tube as shown in Fig. 4, both segments snugly engage the tube surface. The radial end surfaces 8 are then spaced from each other, so that they do not interfere with the contact of the segments 1 against the glass surface of the tube.

Figs. 6 and 7

There is shown in these figures a modified form of beam deflector including two semi-annular segments 14. Each segment 14 is provided with an internal groove 15, which is closed at its ends. In the center of the groove 15 is located a bar magnet 16, which is cemented in the groove. Between the ends of the bar magnet 16 and the ends of the groove are located pole pieces 17 of magnetic material. This material may be a mixture of iron filings and shellac, or some other magnetic powdered material mixed with a suitable binder, or it may be a powdered and sintered magnetic material. Instead of using a plastic mixture, bars of magnetic material may be used as pole pieces.

In the embodiment of Figs. 6 and 7, each of the segments carries a magnetic element consisting of one magnet and two pole pieces. This magnetic element defines a magnetic circuit having a semi-annular portion of magnetic material and a diametrical portion extending through the space between the ends of the semi-annular portion.

When the two segments 14 are assembled on the neck 11b of a cathode ray tube, as shown in Fig. 7, the segments are arranged with their magnets in opposition. In other words, the north pole piece of one segment is placed adjacent the north pole piece of the other segment. This arrangement allows the diametrical portions of the magnetic circuits of the two magnetic elements to aid each other so as to produce a concentrated magnetic field shown at 18, which extends diametrically across the neck 11b of the tube with little or no spreading or distortion. It has been found that such a magnetic field is very desirable in a beam deflector, since its effect on the beam may be more precisely controlled than is the case with other field configurations.

Each segment 14 is provided at each end with a projection 19 and a recess 20. By arranging the two projections in this manner, it can be assured that if the magnets 16 are all inserted with the proper polarity in relation to the projections 19 and recess 20, that the complete beam deflectors, when assembled, will have their magnetic polarities extending in the proper directions.

Fig. 8

There is shown in this figure another modified form of beam deflector embodying the invention. This beam deflector includes two segments 21 and 22. The segment 21 carries a magnet 23, there being no magnet in the segment 22. Pole pieces 24 of plastic magnetic material are provided, similar to the pole pieces 17 of Figs. 6 and 7. There are also provided pole piece extensions 25, which project circumferentially beyond the ends of the segment 21. This arrangement of the

pole pieces does not produce a concentrated magnetic field configuration as the arrangement of Figs. 6 and 7, but nevertheless has an advantage of simplicity and economy of construction.

We claim:

1. A beam deflector for a cathode ray tube, comprising an annulus formed by a plurality of segments having interfitting end portions and adapted to encircle the neck of a cathode ray tube, a yieldable tension band encircling said segments to retain them frictionally in place on said tube neck, and a permanent magnet carried by one of said segments.

2. A beam deflector for cathode ray tubes as defined in claim 1, in which said segments are formed of non-magnetic material substantially softer than glass.

3. A beam deflector for cathode ray tubes as defined in claim 1, in which said segments are formed of moldable plastic material.

4. A beam deflector for cathode ray tubes as defined in claim 1, in which said annulus comprises two substantially semi-annular segments.

5. A beam deflector for cathode ray tubes as defined in claim 1, in which the edges of the segment surfaces which engage the tube are bevelled to aid the removal of the annulus over the base of the tube.

6. A beam deflector for cathode ray tubes as defined in claim 1, in which the segment carrying the magnet has in its inner surface a magnet receiving recess deeper than the thickness of the magnet, so that the magnet does not contact the surface of the tube.

7. A beam deflector for cathode ray tubes as defined in claim 1, in which said interfitting end portions comprise a pin projecting from one end of each segment and a pin-receiving socket in the other end.

8. A beam deflector for cathode ray tubes as defined in claim 1, in which said band is sufficiently yieldable to permit separation of the segments far enough for installation or removal of the annulus over a tube base of larger diameter than the tube neck.

9. A beam deflector for cathode ray tubes as defined in claim 1, in which said interfitting end portions are substantially radial plane surfaces, with a pin projecting from the surface at one end and a pin-receiving socket in the surface at the other end, and said segments are slightly shorter than the length required to form a complete annulus, so that when assembled on a tube, said plane surfaces are slightly spaced.

10. A beam deflector for cathode ray tubes as defined in claim 1, in which said interfitting end portions comprise a projection on one end of each segment and a projection receiving recess on the opposite end, said projections being long enough to remain in engagement with the cooperating recesses during the segment separation required for installation or removal.

11. A beam deflector for a cathode ray tube, comprising an annulus formed by two substantially semi-annular segments of moldable plastic material and adapted to encircle the neck of a cathode ray tube, said segments having inter-

fitting end portions in the form of substantially radial plane surfaces with a pin projecting from the surface at one end and a pin-receiving recess in the surface at the other end, said segments

5 having bevelled edges on the tube-engaging surfaces and each having a central, axially extending recess for receiving a bar magnet, a magnet in each said recess, said recesses being deeper than the magnets so that the magnets do not engage the tube, said segments having a central peripheral groove in their outer surface, and a yieldable tension band in said groove for holding said segments assembled as an annulus.

10 12. A beam deflector for a cathode ray tube, comprising an annulus formed by two substantially

15 semi-annular segments of moldable plastic material and adapted to encircle the neck of a cathode ray tube, said segments having interfitting end portions in the form of substantially

20 radial plane surfaces with a pin projecting from the surface at one end and a pin-receiving socket in the surface at the other end, said segments having bevelled edges and each having a central, axially extending recess for receiving a bar mag-

25 net, a magnet in each said recess, said recesses being deeper than the magnets so that the magnets do not engage the tube, said magnets being arranged with their polarities in the same direction with respect to the pin and socket of their

30 associated segment, and a yieldable tension band for holding said segments assembled as an annulus.

13. A structure for supporting a permanent magnet beam deflector on the neck of a cathode

35 ray tube, comprising a plurality of annular segments having interfitting end portions and co-operating to form a substantially complete annulus when assembled with said ends interfitted, said annulus being adapted to encircle the neck

40 of a cathode ray tube, and a yieldable tension band encircling said segments to retain them frictionally in place on said tube neck, at least one of said segments having a recess for receiving a permanent magnet.
